BY HIS ATTORNEY

Martin J. Schindler

UNITED STATES PATENT OFFICE

HARRY HERTZBERG, OF BROOKLYN, NEW YORK, ASSIGNOR TO HERTZBERG PATENTS INC., OF NEW YORK, N. Y., A CORPORATION OF NEW YORK

MOP HEAD

Application filed June 15, 1931. Serial No. 544,462.

This invention relates to mop heads and particularly to that type thereof which is used for wringer mops and which may be detachably held on a mop handle by means of a sleeve slidably and rotatably mounted on the handle and suitable fastening means for the mop head at one end of the handle.

The present invention has for one of its objects the improvement of the mop head to make it more durable than heretofore, while another object of the invention is an improvement in the manner of fastening the mop material more rigidly to the sleeve.

It has been a defect of mops of this type that the mop pad which is usually tied to the rotatable sleeve by tie wires became loose thereon and the sleeve rotated within the pad during the twisting operation which prevented the wringing of the pad and made the mop practically useless. This defect is completely eliminated by the present invention.

With these and other objects in view the invention consists in novel methods of construction and arrangements of parts which will become clearer as the description progresses and which are illustrated in the accompanying drawing which forms a material part of this disclosure and in which:

Fig. 1 is a plan view of a sheet of mop material ready to be formed into a mop head.

Fig. 2 is a front elevation of a completed mop head attached to a mop handle.

Fig. 3 is a side elevation of Fig. 2.

Fig. 4 is a rear elevation of the upper part of Fig. 3 in the direction of the arrow at that figure.

Fig. 5 is an enlarged sectional elevation of the upper part of the mop head on line 5-5 of Fig. 6.

Fig. 6 is an enlarged sectional plan on line 6-6 of Fig. 5.

Fig. 7 and Fig. 8 illustrate each diagrammatically the manner of winding one of the tie wires around the sleeve 14 so that they cross each other on opposite sides of the sleeve.

Referring to Fig. 2 of the drawing, 10 is a mop handle provided at its lower end with a looped yoke 11 which holds a mop head 12 removably attached thereto by means

of a loop or sheath 13 formed by the mop pad, into which one of the yoke bars is inserted, so that the mop pad extends transversely from the mop axis in opposite directions.

The mop handle carries a tubular sleeve 14 which forms a part of the mop head and is slidably and rotatably mounted on said handle. To said sleeve the ends of the mop pad are fastened in an improved manner which is hereinafter described.

The mop pad consists of a plurality of soft cords 15 arranged longitudinally parallel to each other providing a warp. (See Fig. 1.) Both ends of the warp cords 15 are hemmed in transversely by bands 16. Between these ends, at spaced distances from each other the warp cords 15 are woven tightly together by means of the woof threads 17 to form a fairly rigid fabric. These woven portions are arranged in those places where the mop pad is subject to greatest wear and particularly where it is attached to yoke 11 and sleeve 14. For attachment to the yoke a wide woven portion 18 is provided midway between the end bands 16 of the pad, the narrower woven portions 19 near the ends strengthen the pad where it is attached to sleeve 14 and surround the lower end thereof. The other woven portions prevent the free mop cords between them from unduly spreading and help to consolidate the mop pad.

To form a mop head the pad shown in Fig. 1 is first doubled upon itself at its center within woven portion 18 and a band 20 is sewed around both faces of the pad near the ends of portion 18, thus forming a sheath 13. The hemmed ends 16 are bent inwardly, placed against opposite sides of sleeve 14 at its lower end, and fastened thereto as hereunder described.

The lower, cylindrical part of sleeve 14 is provided with two grooves 21 spaced from each other and provided with teeth 22 transverse of the grooves. (See Figs. 5 and 6.) Near the lower end of sleeve 14 and below grooves 21 two apertures 23 extend transversely through sleeve 14 on opposite sides of mop handle 10. Through each of these apertures a tie wire 24 is threaded, these wires are wound about the mop pad in opposite

directions, as illustrated in Figs. 7 and 8. Each of these wires presses the mop material into the grooves 21 and against the teeth 22 thereof. The ends of each tie wire are twisted together at 25 as shown in Figs. 5 and 6.

5 By passing the tie wire through a transverse aperture of the sleeve 14 and around two grooves the wire will cross itself and rotation of the wire on the sleeve is absolutely 10 prevented in one direction, a short, lost motion is however possible in opposite direction. But by winding two such wires in opposite directions about the sleeve as described, their combined crossings prevent not only any rotary movement but also the short lost motion 15 in either direction, of mop material relative to the tie wires and sleeve. In addition thereto the teeth within the grooves engage the mop material and resist the strongest turning effort exerted during the wringing operation 20 of the mop head.

While I have thus described a preferred form of my invention it shall be understood that modifications may be made in the design 25 and arrangement of parts, or in the construction of details which come within the scope and spirit of the invention as claimed.

Having thus described my invention, what 30 I claim as new and desire to secure by Letters Patent is:

1. In a mop, a holding member having peripheral grooves, a ridge between said grooves, a mopping pad, wires encircling said pad and said holding member, pressing said pad into said grooves, said wires passing over said ridge and cross each other on said holding member for securing said pad to said holding member.

2. In a mop, a rotatable sleeve, a mopping 40 pad, said sleeve having peripheral grooves and wires passing into the wall of said sleeve and encircling said pad and sleeve in line with said grooves and crossing each other on the exterior of said sleeve to secure one end of 45 the pad to the sleeve.

3. In a mop, a handle, a sleeve slidably and 50 rotatably mounted thereon, said sleeve being formed with openings passing interiorly thereof from side to side and with peripheral grooves on its exterior surface, teeth formed in said grooves, a mopping pad, one end of said pad encircling said sleeve and having an inturned edge with overlapped portions over said grooves and wires passing through said 55 openings and across each other on the exterior of said pad and passing around said pad in the plane of said grooves to secure said inturned edge in said grooves whereby movement of said edge relative to the sleeve is 60 prevented.

4. In a mop, a handle, a rotatable and 65 slideable sleeve thereon, a looped member on one end of said handle, a mopping pad having one of its ends detachably secured to the looped member, and means for fixedly securing the

other end of said pad to the sleeve, said means including a pair of wires spirally wound around the end of said pad encircling said sleeve, one of said wires being wound there-around in one direction and the other in the 70 opposite direction.

5. In a mop, a handle, a sleeve rotatably and slidably mounted on said handle, said sleeve being formed with spaced openings, a mopping pad having one end encircling said sleeve, a wire encircling said end of the mopping pad, said wire passing through said openings and having its ends twisted together to prevent rotary movement of said pad on the sleeve.

6. In a mop, a handle, a sleeve rotatably and slidably mounted on said handle, said sleeve being formed with peripheral grooves on the exterior of its body portion and with spaced transverse openings extending from side to side of the body portion, a mopping pad and means for securing said pad on said sleeve and for preventing rotary movement thereon, said means comprising a pair of wires encircling said pad in the plane of said peripheral grooves and passing through said transverse openings, said wires being crossed on the exterior of said sleeve and having their ends twisted together.

Signed at New York, in the county of New York and State of New York this 8th day of June A. D. 1931.

HARRY HERTZBERG.
